UNITED STATES PATENT OFFICE.

HENRY JAMES GAUTHIER, OF PLAINFIELD, NEW JERSEY, ASSIGNOR TO GAUTHIER & CLARKE, OF PLAINFIELD, NEW JERSEY, A COPARTNERSHIP CONSISTING OF SAID GAUTHIER AND FRANK B. CLARKE.

CARBURETER.

1,279,856.

Specification of Letters Patent. Patented Sept. 24, 1918.

Application filed August 4, 1917. Serial No. 184,509.

To all whom it may concern:

Be it known that I, HENRY JAMES GAUTHIER, a citizen of the United States, and resident of Plainfield, county of Union, 5 State of New Jersey, have invented certain new and useful Improvements in Carbureters, of which the following is a specification.

My invention relates to carbureters for internal combustion engines and has for its 10 objects to simplify and improve the operation of such devices, and to cheapen the cost of manufacturing the same. In the accompanying drawings, I have illustrated a carbureter embodying my invention, but it will 15 be obvious that many changes in detail can be made without going outside of the scope of my invention as defined in the claims.

In the drawings:

20 Figure 1 is a longitudinal central section; Figs. 2 and 3 are plan and bottom detail views respectively;

Fig. 4 is a plan detail view of another part;

25 Figs. 5 and 6 are plan and bottom views respectively of another part;

Fig. 7 is an elevation partly in section with some parts removed; and

Fig. 8 is a detail elevation.

30 Referring more particularly to the drawings, the general organization is shown in Fig. 1, in which 1 is a casting having a substantially hemispherical mixture chamber 2 and a reduced neck or passage 3 leading 35 to the manifold (not shown) of any internal combustion engine. In the passage 3 butterfly valve 4 is oscillatably mounted on shaft 5 and constitutes the usual throttle controllable from without by any usual or 40 suitable means. Casting 1 has an upper flange 6 providing means for attaching it to the manifold and a lower flange 7 which provides a seat for bolts 8—8, whereby casting 1 is united with flange 9 of the casting 10. 45

10 comprises a central cylindrical block or hub 11 and an outer concentric cylinder 12, 11 and 12 being rigidly connected through webs 13. A neck or extension 14 is connected with a short pipe section 15 by means of 50 any suitable coupling devices, 15 in turn being coupled with fuel pipe 16 leading to the fuel reservoir, not shown. The passage in extension 14 is continued up through the

hub 11, the upper portion of the passage being reduced in diameter and internally 55 threaded to engage the external threads on valve seat member 17. 17 has an enlarged head 18 and a central bore or fuel passage 19. The fuel passage is reduced in diameter at its upper or outer end to the usual 60 dimensions in a needle valve and provides at 20 a seat for the pointed tip 21 of pin 22. Pin 22 is externally threaded and is adjustable with respect to hub 23 of air valve 24. Clamp nut 25 serves to maintain the adjustment. Air valve 24 is reciprocable up 65 and down and is designed to intermittently close the arcuate air passage 26 between the hub 11 and cylindrical wall 12 (see Fig. 4). Valve 24 does not seat directly across the 70 upper surface of hub 11 and cylindrical wall 12, but has on its under side, a pair of concentric annular flanges or skirts 27, 28 which have sliding contact respectively with hub 11 and wall 12, forming an annular guide- 75 way. Stems 29 project downwardly through the holes 30 in webs 13 (see Fig. 4). On the lower or outer ends of stems 29 the nuts 31, reinforced by clamp nuts 32, provide a seat for the springs 33, 34. At their upper ends, 80 springs 33 and 34 seat against the flat ring 35. This ring has on its under side a pair of raised shoulders 36 which are adapted to be embraced by the larger springs 33 to prevent them from being displaced laterally. Similar shoulders on the nuts 31 perform the 85 same functions with respect to the other ends of the springs 33. The smaller springs 34, being of a diameter only slightly larger than the stems 29, do not require any auxiliary 90 retaining device. In order to vary the tension of the springs 33, I interpose a cap 37 between ring 35 and casting 10. Cap 37 has an internal thread engaging an external thread upon the casting and a flange 38 95 against which the ring 35 is pressed by springs 33. It will be obvious that by advancing or retracting cap 37, the tension of springs 33 will be lessened or increased respectively. On the under surface of flange 100 38, I provide a series of radial grooves or scorings two of which are shown at 39 and 40. On the upper face of ring 35, I provide a radial rib 41 which will successively engage the series of radial scorings on the flange 38 105 when cap 37 is rotated, thus furnishing an

indication of the amount of adjustment, as well as a locking device to prevent the cap 37 from turning accidentally.

Referring again to the air valve 24, it will be noted that a series of perforations 42 is arranged in a circle around hub 23 (see Figs. 5 and 6). Furthermore, each of the flanges 27, 28 has one or more V-shaped notches or ports 43, 44 cut in their peripheries for a purpose hereinafter referred to (see Figs. 6, 7 and 8).

The operation of my device is as follows:

The pin 22 is first adjusted to raise the main plate of valve 24 out of contact with hub 11. This insures an absolute closure of the fuel orifice at 20. In this position, the air valve is substantially closed, but not absolutely, because of the ports 43, 44 which are never wholly masked (see Fig. 7). These narrow passages between mixture chamber 2 and the atmosphere, furnish sufficient leakage to prevent disastrous consequences in case of back firing. I have found also that the valve 24 rises and falls with a smoother motion when the ports 43, 44 are constructed as shown. During the suction stroke of each cylinder of the engine, the difference in pressure on opposite sides of the valve 24, will increase from zero to a maximum. At the beginning of the stroke, the difference in pressure will be equalized by the flow of air through ports 43, 44. As the stroke continues, however, the difference in pressure will become too great to be equalized through the ports and valve 24 will rise, carrying with it the stem 22, thus permitting the flow of fuel through port 20. The upward movement of the valve 24 and stem 22 will be resisted at first by the springs 33 and eventually, if the movement continues, by springs 34. The latter spring is shorter and stiffer than the former. This varying of the load of the valve 24 has two important functions; first, it facilitates setting the valve in motion at a time when its inertia would tend to hold it down, and subsequently counteracts the tendency of the valve to rise farther than desired because of its inertia of movement; second, the increased load tends to reduce the supply of air but not the supply of fuel and as a consequence at high speeds the mixture will be richer than at low speeds.

The carbureter described above has no float chamber and throughout has been designed with a view to cheapening the cost of manufacturing and simplifying operation and adjustment.

I claim:—

1. In a carbureter, the combination with parallel air and fuel passages, of air and fuel valves operatively positioned with respect to said air and fuel passages respectively, said valves reciprocating in axial direction and being joined together in a uni-

tary structure, a plurality of stems carried by said unitary structure and presented through the carbureter casing in a direction parallel to the axis of movement of said unitary structure, heads on the outer ends of the said stems, coiled springs mounted on said stems and bearing against said heads, and means for opposing the inward movement of the inner ends of said springs, said means comprising a cap mounted on the carbureter and embracing said stems.

2. In a carbureter, the combination with parallel air and fuel passages, of air and fuel valves operatively positioned with respect to said air and fuel passages respectively, said valves reciprocating in axial direction and being joined together in a unitary structure, a plurality of stems carried by said unitary structure and presented through the carbureter casing in a direction parallel to the axis of movement of said unitary structure, heads on the outer ends of the said stems, coiled springs mounted on said stems and bearing against said heads, and means for opposing the inward movement of the inner ends of said springs, said means comprising a cap mounted on the carbureter and embracing said stems, said cap being adjustable in axial direction.

3. In a carbureter, the combination with a mixture chamber, of a block closing one side of said mixture chamber, a central fuel passage extending through said block, an annular air passage also extending through said block, a valve plate positioned across the inner ends of said fuel and air passages, said valve plate being movable away from said block, a fuel valve carried by said plate and presented toward said fuel passage and concentric annular flanges carried by said plate and engaging the inner and outer walls respectively of said annular air passage.

4. In a carbureter, the combination of a mixture chamber, a reciprocating air valve having skirts or flanges presented toward the incoming air and having air ports in said flanges, an annular guide-way for said flanges, a fuel passage central of the air-valve and a fuel valve carried by the air-valve.

5. In a carbureter, the combination of a mixture chamber, a reciprocating air valve having skirts or flanges presented toward the incoming air and having air ports in said flanges, an annular guide-way for said flanges, spring means tending to close the valve, a fuel passage central of the air-valve and a fuel valve carried by the air-valve.

6. In a carbureter, the combination of a mixture chamber, a reciprocating air valve having skirts or flanges presented toward the incoming air and having air ports in said flanges, an annular guide-way for said flanges, a fuel passage central of the air-

valve and a fuel valve carried by the air-valve, the air-valve having mixture outlets between the flanges and fuel valve.

7. In a carbureter, the combination of a mixture chamber, a reciprocating air valve having skirts or flanges presented toward the incoming air and having V-shaped air ports in said flanges, an annular guide-way for said flanges, a fuel passage central of the air-valve and a fuel valve carried by the air-valve, the air-valve having mixture outlets between the flanges and fuel valve.

Copies of this patent may be obtained for five cents each, by addressing the "Commissioner of Patents, Washington, D. C."

8. In a carbureter, the combination of a mixture chamber, a fuel valve, an air valve mounted co-axially and movable with the fuel valve, having an annular guiding flange ported toward the fuel valve and mixture passages communicating with the mixture chamber between said flange and fuel valve.

HENRY JAMES GAUTHIER.
